W. M. ROSSITER.
THREAD CUTTING SHUTTLE.
APPLICATION FILED FEB. 3, 1921.

1,393,643.

Patented Oct. 11, 1921.

UNITED STATES PATENT OFFICE.

WILLIAM M. ROSSITER, OF SUNBURY, PENNSYLVANIA.

THREAD-CUTTING SHUTTLE.

1,393,643.

Specification of Letters Patent.

Patented Oct. 11, 1921.

Application filed February 3, 1921. Serial No. 442,190.

To all whom it may concern:

Be it known that I, WILLIAM M. ROSSITER, a citizen of the United States, residing at Sunbury, in the county of Northumberland and State of Pennsylvania, have invented certain new and useful Improvements in Thread-Cutting Shuttles, of which the following is a specification, reference being had therein to the accompanying drawings.

10 This invention relates to improvements in shuttles for looms and the like, and the object of the invention is the improvement in the construction of thread-cutting means on a shuttle.

15 Another object of the invention is the production of simple and efficient cutting means attached directly to the threading device in a shuttle.

With these and other objects in view, my 20 invention comprises certain novel combinations, constructions and arrangements of parts as will be hereinafter described, illustrated in the accompanying drawings, and more particularly pointed out in the appended claims.

In the drawings:

Figure 1 is a top plan view of a shuttle, showing the threading device therein, while

30 Fig. 2 is a side view of the shuttle shown in Fig. 1.

Fig. 3 is a sectional view, taken on line 3—3, Fig. 1, and looking in the direction of the arrows.

Fig. 4 is a view, in side elevation, of the 35 threading device with my cutting device secured thereto, while.

Fig. 5 is a front view of the same.

Fig. 6 is a sectional view, taken on line 40 6—6, Fig. 5, and looking in the direction of the arrows.

Fig. 7 is a perspective view of my cutting device.

Referring to the drawings by numerals, 1 designates the shuttle body, and 2 is the 45 threading device common in the art; it will be understood that this threading device is retained within the shuttle body, as shown clearly in Fig. 3.

The original threading device has been 50 machined to provide a pair of depending, guiding lugs 3 and 3^a, Figs. 3 to 5. A stationary guide 4 is fastened, at 5, to the lower portion of the threading device (Fig. 4) and its upper end is fastened to lug 3.

55 My cutting device includes a stationary plate or frame 6 and a swinging guide 7,

The frame 6 lies flat against the side of the threading device (Figs. 4 and 6) and is fastened thereto by means of a screw 8 passing through aperture 9 of the frame, and 60 screwed into the body of the threading device. On the inner end of the frame 6 is a right-angularly-disposed knife blade 10, which blade is positioned over the outer end of the filling thread passage 11 of the threading device 2; the filling thread 12 passes through the thread passage 11, contiguous to the knife blade 10, on frame 6, and is threaded through the eyelet 13 of the spring metallic swinging guide 7; this guide 7 is 65 fastened by rivet 14, to the outer end of the stationary frame 6. The eyelet 13 has an open guide passage 13^a, whereby in threading the shuttle, the thread 12 can be quickly positioned in the eyelet 13.

70 The knife blade 10 is held rigid upon the threading device, but the swinging guide 7 is adapted to permit the right-angularly-disposed eyelet portion 13^b to swing laterally when undue strain is placed upon the 75 thread 12; the eyelet portion 13^b is positioned behind the stationary guide 4 as well as behind the depending lugs 3 and 3^a, whereby in handling the threading device, as when examining the same, or when it is being 80 placed in the shuttle body 1, the delicately-mounted swinging guide will be protected against injury.

85 The threading device is slightly cut away, at 15, to form lugs 3 and 3^a, and when the wire stationary guide 4 is attached, whereupon the cutting device is fastened to the side of the threading device by screw 8, after which the threading device with the cutting means attached thereto, is placed in 90 the shuttle body.

95 The filling thread from the filling carrier or bobbin 16, is threaded through the threading device 2, and through the eyelet 13 of the swinging guide, thence through the opening or eyelet 17 in the shuttle body 1, Fig. 2, whereupon the thread is caused to normally ride or pass over the outer face of the wire guide 4, in the position shown by dotted lines in Fig. 6. When any undue strain is 100 placed upon the thread 12, such as would injure the goods or work being woven, this tightening or possible back-lash of the thread will immediately cause an outward pull or swing of the eyelet portion 13^b of the 105 swinging guide 7, bringing the thread 12 into strong contact with the knife blade 10,

whereupon the thread will automatically be severed.

It is to be noted that I have produced a simple and efficient cutting means attached directly to the threading device in a shuttle, and which means will be actuated by the slightest undue strain or tightening of the filling thread 12, whereupon the filling thread will be cut or severed, preventing 10 injury to the work or goods being woven.

While I have described the preferred embodiment of my invention, and have illustrated the same in the accompanying drawings, certain minor changes or alterations 15 may appear to one skilled in the art to which this invention relates, during the extensive manufacture of the same and I, therefore, reserve the right to make such alterations or changes as shall fairly fall within the scope 20 of the appended claims.

What I claim is:

1. In a shuttle, the combination with a shuttle body, of a threading device provided with a thread passage in said body, and a 25 cutting device attached directly to the threading device and provided with a cutting blade and a swinging guide over one end of the thread passage within the shuttle body.

2. In a shuttle, the combination with a 30 shuttle body, of a threading device secured to said body, a cutting blade on said body, and movable guiding means contiguous to said cutting blade and movable transverse of the threading device.

3. In a shuttle, the combination with a shuttle body, of a threading device provided with a thread passage secured to said body, cutting means extending practically across said passage, and movable guiding means extending across the passage and transverse of the threading device.

4. In a shuttle, the combination with a shuttle body, of a threading device in said body, a frame secured to the side of said 45 threading device and provided with a knife blade extending across a portion of the threading device, and a thread guide secured at one side of the threading device and positioned to move or swing across the front end 50 of said threading device.

5. In a shuttle, the combination with a shuttle body, of a threading device provided

with a body in said shuttle body, said threading device provided with a thread passage and a stationary guide contiguous to said 55 passage, and cutting means and guiding means carried by the threading device and positioned between the body of the threading device and the stationary guide contiguous to the thread passage.

6. In a shuttle, the combination with a shuttle body, of a threading device provided with a body in said shuttle body, said body of the threading device provided with depending lugs and a stationary guide, movable 65 guiding means between the body of the threading device and the lugs and the stationary guide, and cutting means between the body of the threading device and the movable guiding means.

7. In a cutting device for shuttles comprising an angle frame having a knife blade, and a swinging guide fastened at one end to said frame and having near its other end an eyelet positioned contiguous to said knife blade.

8. A cutting device for a shuttle comprising a frame having a screw-receiving aperture and a knife blade at one end, a spring metal swinging guide fastened to one end of the frame, said guide provided with an eyelet portion contiguous to the knife blade, and said eyelet portion provided with an eyelet and an open guide passage communicating with the eyelet.

9. A cutting device for a shuttle comprising a stationary cutting element, and a swinging guiding element carried by said stationary cutting element.

10. A cutting device for a shuttle comprising a stationary cutting element, and a guiding element fastened at one end to the cutting element and adapted to move at its other end across or transversely of the cutting element.

11. A cutting device for shuttles comprising a stationary frame having a screw-receiving aperture and an integral knife blade, a guide against said frame, and means fastening the guide near one end fixedly to the frame whereby the guide may move or swing away from the frame at its other or unfastened end.

In testimony whereof I hereunto affix my signature.

WILLIAM M. ROSSITER.
